UNITED STATES PATENT OFFICE.

CHRISTEN OVERGAARD, OF COPENHAGEN, DENMARK.

CRANK-SHAFT-MILLING MACHINE.

1,080,576.

Specification of Letters Patent.

Patented Dec. 9, 1913.

Application filed December 16, 1911. Serial No. 666,279.

To all whom it may concern:

Be it known that I, CHRISTEN OVERGAARD, engineer, a subject of the Kingdom of Denmark, residing at No. 4 Amager Boulevard, 5 Copenhagen, Denmark, have invented certain new and useful Improvements in Crank-Shaft-Milling Machines; and I do hereby declare the following to be a full, clear, and exact description of the invention, 10 such as will enable others skilled in the art to which it appertains to make and use the same.

In my co-pending application Serial No. 666,280, filed Dec. 16, 1911, I have described 15 an improved method of milling crank shafts or the like, in which the rough crank shaft vertically supported at a single point in a horizontally rotatory clamping table is milled by means of end milling cutters, 20 which can be displaced in relation to each other, and which from different sides independent of each other can be moved toward, transversely to and parallel to the shaft, and the speed of each of which can be regulated 25 in such a manner that vibrations of the shaft during the milling are prevented, and that consequently every source of inaccuracy is eliminated.

The object of my present invention is to 30 construct a machine for milling crank shafts in accordance with said method. This object I attain in the manner hereinafter set forth, reference being had to the accompanying drawings, in which—

35 Figure 1 shows a front view of the machine partially in vertical section, Fig. 2 is a plan of the machine, Fig. 3 shows one of the cutter housings viewed from the center of the table, and Fig. 4 is a partially sectional view of the motor and the gearings between it and the shafts for different feeds, 40 Fig. 5 is a vertical section through one of the slides which shows the motor and the gearings between it and the cutter spindle, Fig. 6 is a view of the lubricating pump and 45 its connections, and Figs. 7 to 10 show various operation stages.

On the bedplate *d* is placed a revoluble table *e* provided with a rack *f* meshing with 50 a pinion driven by the shaft *G*. Said table may be driven at variable speed from a motor *I* (Figs. 2 and 4), the shaft of which is connected to a shaft *11* mounted in a housing *H* and provided with a friction disk *12*, 55 which can be adjusted lengthwise on the shaft by means of a handle *13*. The disk *12*

cooperates with a friction disk *14* fixed to the end of the shaft *G*, so that said shaft is rotated with different speeds according to the position of the friction disk *12*. Upon 60 the table *e* is placed a pair of clamp elements *k*, *k'*, which hold the crank shaft, and are tightened by bolts or the like. The clamps can move diametrically over the whole of the table in such a way that the crank shaft 65 can be rotated bodily about a center which is the center of the table, and at any radial distance therefrom desired. It is of course also possible to rotate the crank shaft, while the same is concentric with the center of the 70 revoluble table.

The bedplate is, on both sides of the table provided with guides, and upon each of these are placed housings *l*, *l'*, which by the aid of screws *m*, *m'* can be moved backward and forward upon the guides at different speeds dependent upon the adjustment of the gear box *H*. In the housings *l*, *l'* are placed slides *n*, *n'*, which move vertically between four guides, whereby accurate 80 and rigid guidance is insured. The vertical motion can *e. g.* be produced by two screws *o*, *o'*, which co-act with nuts upon the slides. The screws are driven by the shafts *p*, *p'*. The shafts *m*, *m'*, and *p*, *p'* are driven from 85 the main shaft *11* in the housing *H*, (Fig. 4). Each of said shafts is provided with a conical pinion *15* engaging two conical pinions *16*, *16* loosely mounted upon the shaft *11*. Between each of said pairs of pinions 90 *16* is arranged a coupling member *17* by which said pinions can be connected to the shaft, and by means of a handle *18* can be brought in engagement with one or the other of said two pinions *16*, thereby causing the 95 corresponding pinion *15* and its shaft to rotate in one direction or in the other.

In order that the housings *l*, *l'* can form a solid and reliable guide for the slides *n*, *n'*, they are connected at the top by means 100 of cross-pieces *q*, *q'*. Motors *r*, *r'* are mounted in the slides *n*, *n'*. Each of said motors drives through pinions *19*, *20* (Fig. 5) a shaft *21* mounted in the slide. Upon said shaft are loosely mounted two pinions 105 *22*, *23* of different size, engaging pinions *24*, *25* also of different size fixed to a second shaft *26* mounted in the slide *n* or *n'*. By means of a coupling member *27* provided with a handle *28* one or the other of the pinions *22*, *23* can be connected to the shaft 110 *21* thereby causing the shaft *26* to be rotated

at a lesser or greater speed. Upon the shaft 26 are loosely mounted two pinions 29, 30 of different size, which engage pinions 31, 32, also of different size fixed to a hollow shaft 33 mounted in said slide n or n' . By means of a coupling member 34 provided with a handle 35 one or the other of the pinions 29, 30 can be connected to the shaft 26, thereby causing the hollow shaft 33 to be rotated at a lesser or greater speed. The spindles s , s' carrying the end milling cutters t , t' are mounted in the hollow shafts 32 in such a manner that they revolve with said shafts, but are lengthwise movable in said shafts. The speed of the motors r , r' can be varied by a controlling device 36 by means of which the current supply to the motor can be regulated. By means of the described arrangement the speed of the cutters t , t' can be regulated independent of each other and to any desired extent. On the other end of the cutter spindles s , s' are crossheads u , u' , which at the same time form thrust bearings for the spindles; the crossheads slide on the guides v , v' , and the spindles can travel out and in by aid of the guide screws w , w' .

To enable the crank shaft to be milled as near to the clamp as possible, there is provided beneath the revoluble table, and about the same center, a pit x , which also serves as a reservoir for the soap water or other lubricant, used during the milling. From the pit the soap water or other lubricant is pumped up through the pipe y (Fig. 6) by a pump 37 driven by a motor 37' which delivers the soap water to pipes 38, 39 connected to flexible tubes z , z' through which the soapy water is fed to hollow spindles s , s' and thence to the cutters t , t' which it leaves just in front of each cutting edge.

When a crank shaft is to be milled the rough forging is placed in the machine in such a manner that the first crank is fixed between the clamps k , k' , which latter are then so adjusted that the axis of the shaft coincides with the center of the table. Then the upper end, that is, the first bearing part of the shaft can be milled. When this first bearing part is finished, the shaft is vertically displaced in the clamps k , k' and again fixed in such a position that the first crank lies immediately over said clamps and that the front and back surfaces of said crank are placed parallel with the clamp slides. Then the clamps are brought so far out to the side, that the axis of the crank pin coincides with the axis of rotation of the table. The crank pin can now for instance be made as shown in Fig. 7 by placing the cutters in a position about half way between those indicated by Figs. 8 and 9, and the milling takes place by turning the table and at the same time bringing the cutters nearer the center for every revolution

of the table by turning the guiding screws w , w' . It is to be remarked, that when one cut is milled by one of the cutters the table can continue quickly in the same direction until the metal is nearing the cutter on the opposite side, which meantime is adjusted to mill a new cut. These operations are discontinued of course when the pin has become round and of required diameter. As the work proceeds the milling is performed on a smaller and smaller radius, and it is therefore preferred by any known means to correspondingly increase the rotatory speed of the table, in such a manner that the work produced by the cutters per unit of time always is the same.

If the crank pin is to be milled cylindrically, one can, when the right diameter is reached, place the cutters as shown in Fig. 5, then turn the table and simultaneously for every revolution of the table bring the cutters sideward nearer the center of the pin until they are standing as shown in Fig. 6 just over the center; then a circular cylindrical surface, the height of which is equal to the diameter of the cutters, is milled.

The milling of the front and back surfaces i , i' takes place by setting the table in such a way that these surfaces lie parallel with the direction of motion of the housings 95 and by moving these forward and backward over the whole length of the surfaces, these surfaces can be finished completely on the machine. The end surfaces of the crank webs 10, 10' can be milled as shown in Fig. 100 8. The shaft is adjusted on the table in such a manner, that the axis of the table lies between the axis of the shaft and the axis of the pin. By milling the end surfaces of the webs with a joint center, the cranks are 105 made lighter, and the corners are not so sharp. It is to be noticed, that with large cranks this operation would practically be impossible on a crank shaft lathe, as this would demand a machine of exceptional dimensions. After having completed the first crank in the way described, the shaft is again vertically displaced in the clamps k , k' and fixed in such a position that its second bearing part can be milled. Thereafter the 115 shaft is again vertically displaced and the second crank is milled and so on. When the upper half of the shaft is milled, the shaft is turned about and the milling is started from the opposite end.

Having now particularly described and ascertained the nature of my said invention, and in what manner the same is to be performed, I declare that what I claim is:

1. In a crank shaft milling machine, the 125 combination with a horizontally revoluble clamping table and a pit beneath said table adapted to take the major portion of the length of the shaft vertically fixed at one point in said clamping table, of end milling 130

- cutters disposed in the immediate vicinity of the point of support of said shaft, means for displacing said cutters in relation to each other, means for moving said cutters from 5 different sides independent of each other toward, transversely to and parallel to the shaft, and means by which the rotary speed of said cutters can be varied independent of one another.
- 10 2. In a crank shaft milling machine, the combination of a horizontal table revoluble about a vertical axis, clamp elements for supporting at one point the shaft held vertically, which clamp elements can slide diametrically upon said table, and a pit beneath said table adapted to take the major portion of the length of the shaft, with end milling cutters, means for displacing said cutters in relation to each other, means for 15 moving said cutters from different sides independent of each other toward, transversely to and parallel to the shaft, and means by which the rotary speed of said cutters can be varied independent of one another.
- 20 3. In a crank shaft milling machine, the combination of a clamp revoluble about a vertical axis, in which the shaft is adapted to be vertically held, with end milling cutters, spindles carrying said cutters, means for moving said spindles in three different 25 directions perpendicularly to each other, means for rotating said spindles, frames for carrying said spindles and their rotating motive elements, and vertical guides for said frames, which guides are rigidly interconnected at the top and bottom.

In testimony whereof, I affix my signature, in presence of two witnesses.

CHRISTEN OVERGAARD.
